(57) **CLAIM**

The ornamental design for an instrument panel for an automobile as shown and described.

DESCRIPTION

FIG. 1 is a first side perspective view of an instrument panel for an automobile in accordance with my new design; FIG. 2 is a second side perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right side elevational view thereof; and, FIG. 8 is a left side elevational view thereof. The rear view and rear surfaces of the instrument panel shown in broken lines form no part of the claimed design. The instrument panel is configured to be mounted to an automobile. A second embodiment of my new design includes the mirror image of the instrument panel shown in FIGS. 1 to 8.
